(57) **CLAIM**

The ornamental design for a jewelry ring head, as shown and described.

DESCRIPTION

FIG. 1 is a perspective view of a jewelry ring head showing my new design;

FIG. 2 is a front elevational view of the jewelry ring head, the rear elevational view being a mirror image thereof;

FIG. 3 is a left side elevational view of the jewelry ring head, the right side elevational view being a mirror image thereof;

FIG. 4 is a top plan view of the jewelry ring head thereof; and,

FIG. 5 is a bottom plan view of the jewelry ring head thereof. The broken lines shown in the drawings represent environmental structure and form no part of the claimed design.
